His Attorney.

UNITED STATES PATENT OFFICE.

AUGUST HENRY ALBERSHARDT, OF CRAWFORDSVILLE, INDIANA.

ATTACHMENT FOR VALISES, &c.

SPECIFICATION forming part of Letters Patent No. 523,503, dated July 24, 1894.

Application filed December 4, 1893. Serial No. 492,799. (No model.)

To all whom it may concern:

Be it known that I, AUGUST HENRY ALBERSHARDT, a citizen of the United States, residing at Crawfordsville, in the county of 5 Montgomery and State of Indiana, have invented a new and useful Attachment for Valises, Satchels, and Grips, of which the following is a specification.

My invention refers more particularly to an 10 attachable and a removable annex for valises, satchels, and grips and has for its object to produce a convenience of the character described whereby a greater packing capacity is obtained without adding but little to the 15 heft of the valise, satchel, or grip and consists in the peculiar construction, combination, and arrangement of the several parts as will be pointed out more minutely in the following description and claims. This object has been fully attained by the annex illustrated in the accompanying drawings forming a part of this specification, in which—

Figure 1 is a perspective view of my invention. Fig. 2 is a sectional view beginning 25 at the line M, M, Fig. 1.

Like numbers of reference indicate corresponding parts throughout both views.

In the construction of my invention, I use an inner side-piece 1, an outer side-piece 2, 30 the folding ends 3, a folding bottom 4, a pliable lid or cover 5, a series of connecting springs 6, a series of fastening straps 7, and a pair of binding cords 8.

The rectangular inner and outer side-pieces 35 1 and 2, being constructed of stiff, bendable leather, canvas, or other like material, are connected and bound at the corners by the springs 6 for the purpose of forming a self-closing annex on being relieved of the contents. A pair of binding cords 8 are secured 40 at the ends of the side-pieces 1 and 2 between the springs 6 for the purpose of limiting the expansion of the annex to the length of the cords.

45 The fastening straps 7 being attached at the corners of the inner side-piece 1 are buttoned over the buttons or studs 9 of the valise, satchel, or grip for the purpose of securing the annex thereon and removing it when 50 desired. A pliable lid or cover 5 is secured to the inner side-piece 1 and provided on the inside near the outer edge with a pair of studs

10 adapted to fasten into the stud-caps 11 of the outer side-piece 2.

The folding ends 3 and bottom 4 are 55 creased so as to fold neatly and closely together and are securely attached to the ends of the side-pieces 1 and 2. The outer side-piece 2 is provided with a series of ordinary stud-caps 10 to receive and clasp the studs 10 60 for the purpose of fastening the lid or cover at different places on the side thereof. A hand-strap 12, secured to the outer side-piece 2 is pulled in opening the annex for the reception or removal of its contents. 65

In using my invention, the annex is attached or removed from the valise, satchel, or grip by simply buttoning or unbuttoning the straps over the studs or buttons on the valise, satchel or grip. By providing a series of 70 stud-caps as shown in the drawings, the lid or cover may be fastened at any place desired on the outer side-piece of the annex. The annex is opened for the reception or removal of an article by simply pulling on the hand-strap, it being self-closing on being released. 75

In the above construction I produce a simple and convenient article that can be easily attached to or removed from a valise, satchel, or grip whereby travelers and tourists may 80 greatly increase the packing capacity of their hand-baggage without adding but little to its heft.

Having thus fully described my invention and shown the operation and advantages 85 thereof, what I claim as new, and desire to secure by Letters Patent, is—

1. An attachment or annex for valises, satchels, and grips having a stiff, bendable inner and outer side-piece connected at the 90 corners by springs for the purpose of forming a self-closing annex and at the ends between the springs by a pair of binding cords for limiting the expansion of the annex to the length of the cords, the folding ends and bottom, the 95 same being creased for being folded neatly and closely together, and the pliable lid or cover provided on the inside near the outer edge with a pair of studs adapted to be fastened into the stud-caps of the outer side-piece, substantially as specified. 100

2. An attachment or annex for valises, satchels, and grips, the same comprising a rectangular inner and outer side-piece, the

inner side-piece being provided at the corners with fastening straps adapted to be buttoned or unbuttoned from the valise, satchel, or grip, the outer side-piece having a series of stud-caps adapted to receive and clasp the studs on the lid or cover whereby it may be fastened at different places to said side-piece, the connecting springs whereby the annex is made self-closing, a pair of binding-cords for limiting the expansion of the annex, the folding ends and bottom adapted

to be closed neatly and closely together, and the pliable lid or cover, having a pair of studs near the outer edge thereof adapted to be fastened into the stud-caps on the outer side-piece at different places, substantially as specified. 15

AUGUST HENRY ALBERSHARDT.
